UNITED STATES PATENT OFFICE.

JOHN CAPLES MALLONEE, OF CHARLOTTE, NORTH CAROLINA.

PROCESS OF OBTAINING SPIRITS OF TURPENTINE FROM WOOD.

SPECIFICATION forming part of Letters Patent No. 781,733, dated February 7, 1905.

Application filed December 23, 1903. Serial No. 186,307.

To all whom it may concern:

Be it known that I, JOHN CAPLES MALLONEE, a citizen of the United States, residing at Charlotte, in the county of Mecklenburg and State 5 of North Carolina, have invented new and useful Improvements in Processes of Obtaining Spirits of Turpentine from Wood, of which the following is a specification.

This invention has relation to the art or process of obtaining spirits of turpentine and cognate substances from their woods, such as yellow pine; and it is the object constituting the invention to not only render the process more efficient and simple than heretofore, but 5 to economize in substantially all of the steps necessary in the process, obviating a number of acts heretofore deemed necessary and substituting new steps which seem to me now to be of very great efficiency and importance. 10 To these ends my invention consists of the improvements which I will now proceed to describe in detail, explaining one of the means that I find suitable for carrying the invention into effect, and subsequently point out the invention specifically in the claims hereto attached.

Of the drawings embodying the before-mentioned means, Figure 1 is a side elevation, parts being represented as broken away, of 5 the so-called "first" still and some of the connecting parts. Fig. 2 is a similar view of the so-called "second" still. Fig. 3 is a cross-sectional view of one of the stirrer or mixer arms, showing the location of a perforated steam-pipe located thereon. Fig. 4 is a diagrammatic view of a common still hereinafter referred to, parts being represented as broken away for the sake of clearness. Fig. 5 is an end view, partly in section, of the central hole 10 shaft and means for attaching the mixer blades or arms to the shaft and showing also some important details of construction. Fig. 6 is an end view, partly in section, showing some details of construction in connection 5 with the mixer-arms, &c.

Similar indicating numerals or marks indicate the same parts or features, as the case may be, throughout.

Heretofore the process generally employed 10 for securing turpentine and other oils or use-

ful substances from pine wood has been carried on in steel retorts by reducing the wood to charcoal under high temperatures, and, in short, by the process known as "destructive distillation," the necessary apparatus employed 55 being very costly and short-lived, owing to the high temperatures employed in its operation. By my new process I carry on the operation under low-temperature conditions incident to the use of steam at ordinary boiler-pressures. 60

Before describing a form of apparatus that I may employ I will give a brief description of the process and some of the reasons for its use by me.

It is well known that such substances as creosote and phenol oils do not exist in pine woods in a state of nature, but are produced in the retort during the decomposition of the wood by the high temperature employed. On the other hand, the resinous or fatty bodies native to the wood separate into turpentine and rosin at about the temperature or a little higher than boiling water. In the old method of destructive distillation as long as the water contained in the wood was being driven off in 75 the form of steam the turpentine was carried over and condensed in the coil, and the rosin was at the same time drawn out of the wood and fell or dripped to the bottom of the retort. This first flow of turpentine-oil was in the 80 form of almost pure spirits, but was soon contaminated by the heavier oil produced, this latter phase being induced by the difficulty had in causing the steam to penetrate and be emitted from the pores of the wood 85 in bulk. It is also well known that even the highest grade of oils produced from pine wood under the process of destructive distillation are liable to be decomposed into inferior and heavier bodies by contact with too high 90 heats, and hence in order to guard against this loss, which was constantly occurring, has been one of the designs or purposes of my new process, which, as before stated, is operated under relatively low temperatures exclusively. As experience has shown that it is due to the inability of the steam and low heat to penetrate the pores of the wood without raising the latter to a dangerous degree of 95 heat, I have conceived the idea of disintegrat- 100

ing or defibrating the wood and then subjecting each disintegrant or individual fiber to a thorough steaming with a view of extracting the turpentine and rosin of merchantable purity and odor and in large quantities. In my experiments and practice I have found that simple ebullition or boiling of the water carried into the retort with the defibrated wood in filling the retort and steaming such mass 5 while it is in a substantially still or quiet condition in the retort does not raise or volatilize certain oils sought after in the mass under treatment at the beginning of distillation with sufficient thoroughness and rapidity to 10 carry them over and prevent their decomposition into or contamination by inferior and heavier bodies, but that in order to fully secure the oils sought after in their purity it is necessary to agitate the mass in such manner 15 as that the tendency will be to raise portions of the mass below toward the top and raise other portions below to the top, plunging top portions to or toward the bottom, and while this agitation is proceeding to constantly add 20 live steam to the mass.

I need not here give a description of my method of reducing the wood to a fibrous condition, as this can be done by any of the known ways of reducing wood to a chippy, pulpy, or 25 fibrous condition suitable for treatment; but I will describe means which may be employed in carrying out the process forming the subject-matter of case.

In the initial or first step or steps of the 30 means shown for carrying my improvements into effect I use a still 1, built in the form of a cylinder, of any desired capacity, having a hollow steel shaft 2 running through it and journaled in stuffing-boxes 3. This shaft carries a number of stout stirrer or mixer arms 35 or blades 4, secured rigidly to it by means of intermediate cast-iron collars 5 working on a feather and fastened by set-screws 6, the shaft and attached arms being revolved by bevel-gearing 7, of well-known construction, operated from any suitable prime motor.

The stirrer or agitating arms are grooved in their rear edges upward, as at 8, for the reception of the perforated pipes 9, extended 40 therein, the said pipes 9 being connected with pipes 10 by couplings 11, which connect the pipes 9 and 10, the latter connecting with the hollow of the steel shaft 2, (see particularly Figs. 3 and 4,) this construction and arrangement of parts being provided for the purpose of admitting steam from the hollow of the shaft 2 into the perforated pipes 9 and to cause 45 said steam to commingle with the mass of fiber or pulp under treatment as the beater or stirrer arms are revolved. The pipe 12, carrying steam into the hollow shaft, receives steam from the engine-boiler and is attached to the central hollow shaft by means of a stationary stuffing-box 13, clamped rigidly to the pipe 50 by the stuffing-box 13, suitably packed and

lubricated, so that the shaft and stuffing-box 13 may move while the pipe 12 remains stationary.

At the top of the still 1 is a vapor-pipe 14, connecting with an ordinary coil-condenser 70 15, and at the bottom the still, provided with a large draw-off gate 16 and a suitably large manhole-opening 17, is formed in the top for filling the still with pulp.

The action of the still is as follows: The 75 shaft 2 being set in motion, the pulp or defibred wood is fed in through the manhole 17 by any suitable means, some water being run in at the same time to render the movement of the pulp and the mixers more easy. As 80 soon as the still is filled the top opening or manhole 17 is closed, when steam is turned into the closed steam-coil 18, arranged in the bottom of the still. When the mass becomes thoroughly hot, which can be ascertained from 85 feeling the vapor-pipe 14 with the hand or in any other suitable way, live steam is turned into the hollow shaft by opening the gate or valve 19, with the double effect of aiding in the agitation of the pulp and at the same time 90 bringing over into the vapor-pipe 14 the turpentine, which appears at this point somewhat discolored, necessitating further refining by simple distillation. The agitation of the mass under treatment, substantially as described, 95 at the same time constantly adding live steam, is an important feature of the invention, since it effects a quicker and more thorough distillation of the oils first obtainable and preserves them for a longer time from the beginning of 100 distillation against contamination by the heavier oils than could be otherwise the case, even with the defibration of the wood. As soon as the flow of turpentine ceases at the worm 105 steam is shut off from the hollow shaft, the hollow shaft is stopped, but the flow of steam is maintained through the closed coil 18 in the bottom of the still for some time longer or until it is judged that the rosin has collected 110 well on the bottom in a fluid state, at which time it is drawn off from the draw-off gate 16 somewhat mixed with pulp, but capable of being worked for rosin-oils or strained out as a low-grade commercial rosin. The pulp after 115 the rosin has been taken out is then run into a still 19, which I call a "digester," where it is now treated to a weak solution of caustic soda or potash and where it is subjected to a pressure varying from sixty to one hundred pounds, this being for the purpose of preventing the foaming over of the soapy liquid 120 into the still and at the same time of driving into the fiber the soda solution with a view of leaching out what further resonance matters it may contain. The excess of pressure is fed 125 through a regulating-valve into an ordinary condenser, and, as before said, it has been found that it prevents the foaming over of the soapy liquid into the still. Moreover, I have found that by carrying relatively high 130

pressure I am enabled to carry on this part of the process of distillation in an entirely satisfactory manner. This still 19 may be heated by closed steam-coils 21, steam-jackets, 5 (not shown,) or perforated coils 22, the pressure being ascertained by a pressure-gage 23. A steam-gage may also be applied to still 1. As soon as the distillation ceases—that is, as soon as it is ascertained that the wood does 10 not contain any more turpentine—the still is gradually shut, pressure being blown off slowly and the contents discharged. The wood is now in a finely-divided state and can be used for a variety of purposes—as, for instance, paper-making, briquetting for kindling-blocks, or reduced to charcoal in the 15 form of bricks, &c.

The oil resulting from this process is dark in color, but with a pleasant turpentine and 20 pinene odor, and can readily be rendered water-white by simple distillation in any ordinary still, the final product being in no manner different from ordinary commercial spirits of good quality.

25 It is to be distinctly understood that I have not shown nor described all of the ways in which an apparatus may be constructed or used for carrying into effect my improvements in the art of producing turpentine, rosin, and 30 their cognate ingredients from pine wood, since it is obvious that these may be varied, and, moreover, do not form any substantial part of my present invention. Indeed, I have conceived of other means than those shown 35 and which from continued practical experience now seem quite as valuable as those herein disclosed and may form subjects of separate applications. Furthermore, I do not bind myself to the precise manner of procedure which the use of some words here 40 would imply. For example, in speaking of "defibrating" or "disintegrating" wood I do not mean to be understood as binding myself to performing this act absolutely or in the con- 45 fined sense of the words employed, but defibrating or disintegrating the wood so as to separate it into its integrant particles to a degree or extent only that will enable me to carry out fairly the nature and spirit of my 50 invention.

What I claim is—

1. The art of extracting turpentine and its

cognate substances from wood, which consists in confining the mass under treatment, agitating it mechanically throughout its entire body 55 in such manner that its tendency will be to raise, with certainty, portions of the mass below toward the top and raise other portions below to the top, plunging top portions to or toward the bottom, and at the same time subjecting the mass throughout its entire body to steam at a relatively low temperature.

2. The art of extracting turpentine and its cognate substances from wood, which consists in confining the mass under treatment, sub- 65 jecting it to heat and steam at a temperature of somewhat above 212°, agitating it mechanically throughout its entire body in such manner that its tendency will be to raise, with certainty, portions of the mass below toward 70 the top and raise other portions below to the top, plunging top portions to or toward the bottom, and at the same time subjecting the mass throughout its entire body to steam and at a relatively low temperature. 75

3. The art of extracting turpentine, rosin and their cognate substances from wood separated into substantially its integrant fibers, which consists in confining the mass to be treated and subjecting it to heat and steam at 80 a relatively low temperature, thoroughly agitating the mass, substantially as described, during this operation and constantly adding live steam, then removing the rosin and subjecting the mass to pressure varying between 85 sixty and one hundred pounds.

4. The art of extracting turpentine, rosin and their cognate substances from wood which consists in first defibrating the wood, as described, and then distilling it by means of 90 steam applied to and permeating the entire mass, then removing the resinous substance and treating the pulp to a weak solution of caustic soda or potash, and finally treating it to heat and pressure varying from sixty to 95 one hundred pounds.

In testimony whereof I have signed my name to this specification in the presence of two subscribing witnesses.

JOHN CAPLES MALLONEE.
